ANTENNA

George B. Vernier, Chicago, and Richard L. Rost,
Park Ridge, Ill., assignors to Zenith Radio Corporation,
a corporation of Illinois

Application November 13, 1945, Serial No. 628,149

4 Claims. (Cl. 250—33)

1

This invention relates to radio antennas, and more particularly to such antennas which may be conveniently collapsed when not in use or readily extended for more efficient reception.

Automobiles, portable radio receivers, and like equipment have frequently been provided with rod antennas formed of telescoping sections which may be telescoped together into a small space when they are not in use, and which may be readily extended for greater signal pickup when the radio equipment is in use.

It is an object of the present invention to provide such an antenna with simple rugged and improved means for retaining it in stored position and yet actuatable to release it quickly when desired so that it may be readily extended.

The features of the present invention which are believed to be novel are set forth with particularity in the appended claims. The present invention itself, both as to its organization and manner of operation, together with further objects and advantages thereof may best be understood by reference to the following description taken in connection with accompanying drawings in which:

Figure 1 is an elevational view, partly in section, of an antenna arranged in accordance with the invention;

Figure 2 is a similar view of the same antenna in operated position; and

Figure 3 is a perspective view of the antenna in the position of Figure 2 arranged in a cabinet.

In Figure 1 an antenna 10, provided with an electrical connection 10a for the input terminal of a radio receiver, is arranged in a housing 10b, which may, for example, be the cabinet of a portable radio receiver or the hood or top of an automobile or the like. The antenna 10 is formed of a plurality of concentric tubular sections 11, 12, 13, 14 and 15, surrounding a concentric rod 16, all nested together. The rod 16 is provided with an enlargement 17 on its lower end, and the tubular section 15 is provided with a corresponding reduced portion at its upper end, so that, when the rod 16 is raised to cause the enlargement 17 to encounter the upper end of the tubular section 15, the tubular section 15 is drawn after the rod 16.

In similar fashion, the tubular sections 15, 14, 13 and 12 are provided with enlarged portions at their lower ends which cooperate with corresponding reduced portions at their upper ends, with the result that steady withdrawal upward of the rod 16 draws after it in succession sections 15, 14, 13 and 12 to form a tall rod antenna.

5 Satisfactory electrical connections between each of the sections is provided for the transfer of radio frequency current.

On the upper end of the center rod 16 there is provided an enlarged piece 18 which is preferably of insulating material, arranged to lie flush within the enclosure in which the antenna 10 is mounted. One side of the piece 18 is provided with a ledge 19 which is engaged by a spring catch 20 when the piece 18 is in its lowermost position. The spring catch 20 is fastened at its lower end by means of a band 21 around the outer tubular member 11 of the antenna 10, and the spring 20 is provided at its upper end with a manual operating part 22, which may be depressed to release the spring 20 from the ledge 19 and allow the withdrawal upward of the piece 18 and the rod 16 together with the tubular sections of the antenna 10.

10 Within the outer tubular part 11 of the antenna 10, below the lower ends of the tubular sections 12, 13, 14, and 15, an enclosing member 23 is provided which supports a coil spring 24 within the tubular section 11. The coil spring forces a washer 25 upward against the lower end of the enlargement 17 of the center rod 16. The pressure of the spring 24 therefore holds the ledge 19 of the piece 18 firmly upward against the spring catch 20 so that the upper contour of the piece 18 is flush with the housing within which the antenna 10 is mounted.

15 The washer 25 is preferably provided with an indentation 26 at its center within which the lower end of the enlarged part 17 of rod 16 fits.

20 When the manually operable portion 22 of the spring catch 20 is depressed, so that ledge 19 is released, the spring 24 rapidly forces the center rod 16 and the piece 18 upwards to a position where the piece 18 may be readily grasped to pull the entire antenna out to its full length.

25 In Figure 2, the arrangement is illustrated with the parts in the positions assumed just after the spring catch 20 has been released from ledge 19. All parts are identical with those illustrated in Figure 1, and like reference characters are applied to them. The pressure of the spring 24 is sufficient to throw the rod 16 upward so that it comes to rest with the enlarged end 17 some distance above the washer 25. The washer 25 is pressed upwards against stops formed by depressions 27 in the wall of the outer tube 11 of antenna 10. The depressions 27 are desirable to avoid the possibility that washer 25 could be turned over at some time when the enlarged part 17 of rod 16 is not in engagement with it.

In Figure 3, the cabinet 28 of the portable radio receiver is provided with a back lid 29 in the upper edge of which a recess 30 is provided within which the piece 18 may be depressed. Adjacent the recess 30 the manually operable part 22 of the spring catch 20 is arranged, and the parts are illustrated in the position assumed just after the manual part 22 has been moved to release piece 18 for upward movement. As illustrated, piece 18 is ready to be grasped so that the whole antenna may be pulled out to extended position for operation.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

We claim:

1. An extensible telescopic antenna comprising: a plurality of tubular members and a rigid central member coaxially disposed in nested relation when said antenna is in a retracted condition and disposed in axial alignment when said antenna is in an extended condition, said central member having a length intermediate the lengths of the inner and outer ones of said tubular members; a compression spring axially disposed within said outer tubular member; releasable means for retaining said central member against the restoring force of said spring; and means for suddenly arresting expansion of said spring upon release of said central member retaining means thereby to launch said central member axially to a position for ready extension of said antenna.

2. An extensible telescopic antenna comprising: a plurality of tubular members and a rigid central member coaxially disposed in nested relation when said antenna is in a retracted condition and disposed in axial alignment when said antenna is in an extended condition, said central member having a length intermediate the lengths of the inner and outer ones of said tubular members; a compression spring axially disposed within said outer tubular member; a releasable catch mechanism for retaining said central member against the restoring force of said spring; and a limiting arrangement for suddenly arresting the restoring action of said spring upon release of said catch mechanism thereby to launch said central member axially to a position for ready extension of said antenna.

3. An extensible telescopic antenna comprising: a plurality of tubular members and a rigid

central member coaxially disposed in nested relation when said antenna is in a retracted condition and disposed in axial alignment when said antenna is in an extended condition, said central member having a length intermediate the lengths of the inner and outer ones of said tubular members; a compression spring axially disposed within said outer tubular member; a releasable catch mechanism for retaining said central member against the restoring force of said spring; and a limiting stop disposed within said outer tubular member for suddenly arresting the restoring action of said spring upon release of said catch mechanism thereby to launch said central member axially to a position for ready extension of said antenna.

4. An extensible telescopic antenna comprising: a plurality of tubular members and a rigid central member coaxially disposed in nested relation when said antenna is in a retracted condition and disposed in axial alignment when said antenna is in an extended condition, said central member having a length intermediate the lengths of the inner and outer ones of said tubular members; a compression spring axially disposed within said outer tubular member; a washer slidably supported within said outer tubular member and in engagement with said compression spring; a releasable catch spring engageable with said central member for retaining said central member in contact with said washer against the restoring force of said compression spring; and a stop disposed within said outer tubular member for limiting axial movement of said washer suddenly to arrest the restoring action of said compression spring upon release of said catch spring thereby to launch said central member axially to a position for ready extension of said antenna.
